UNITED STATES PATENT OFFICE.

EARL J. SMITH AND HAROLD V. GLOS, OF CHICAGO, ILLINOIS, ASSIGNORS TO UNDER-WRITERS LABORATORIES, INC., OF CHICAGO, ILLINOIS, A CORPORATION OF ILLINOIS.

FIRE EXTINGUISHER.

1,408,541.

Specification of Letters Patent.

Patented Mar. 7, 1922.

Application filed February 26, 1919. Serial No. 279,420.

To all whom it may concern:

Be it known that we, EARL J. SMITH and HAROLD V. GLOS, citizens of the United States, residing at Chicago, in the county 5 of Cook and State of Illinois, have invented a certain new and useful Improvement in Fire Extinguishers, of which the following is a specification.

This invention relates to fire extinguishers 10 having a tank adapted to contain an alkaline solution and a bottle or other container adapted to contain an acid, the apparatus being designed to be inverted when desired for active use; in such event the acid discharge 15 charges into the solution of the tank and generates a pressure sufficient to eject the solution through a suitable hose and nozzle. These extinguishers must, of course, be re-filled after the contents has been discharged 20 and whether discharged or not the contents should be renewed periodically to insure efficient operation. It is common practice to support the acid container in a cage within the tank, and the object of the invention is 25 to improve the cage and associated parts so as to simplify the operation of inserting and removing the acid container into and from the cage and to insure the proper positioning of the acid container when the various 30 parts of the extinguisher are assembled.

We accomplish our object by the mechanism illustrated in the accompanying drawings in which—

Figure 1 is a side elevation of the extinguisher, the tank and cap being shown in section.

Figure 2 is a side elevation of the container and cage, the latter being shown in vertical section. This view illustrates the 40 co-action of the parts during the act of introducing or removing the acid container.

Figure 3 is a perspective view of the cage proper,

Figure 4 is a perspective view of the ring 45 which forms part of the cage and cooperates with it to retain the acid container.

Figure 5 is a fragmentary perspective showing a modified form of lug for retaining the bottom of the acid container.

50 Like reference numerals refer to like parts throughout the different figures.

Referring to the drawings, the tank 1 has a screw cap 2, and this cap has a ring 3 at the top which forms a base for the apparatus when inverted. These parts all conform

to present practice. In the form selected to illustrate the invention the cage has a flanged ring 4 at the top which fits within the mouth of the tank, the horizontal flange resting upon internal lugs 1^a in such manner that when the cap is screwed down the ring will be loosely held in position. Depending from the ring 4 are bars 5, 5 carrying cross bars 6, 6 at the lower end, these cross bars forming a seat for the acid container 7. 60 The number of depending bars is immaterial except that the cage is open at one side to admit the acid container into the cage. In the present design there are three of these bars located 90° apart. At the fourth 70 or open side of the container a lug 8 rises from the end of one of the cross bars, the purpose of the lug being to confine the lower end of the acid container laterally, and prevent it from slipping sidewise from its seat. 75 Near the top of the cage are pins 9, 9 which extend radially inward. They are here shown to be three in number, one for each of the bars 5. The purpose of these bars is to loosely confine and guide the ring 12 80 which is here shown in the form of a hollow cylinder with its axis coincident with the axis of the cage, and having vertical slots 13 through which the pin 9 projects. The slots also constitute openings through which 85 the acid may escape into the interior of the tank when the device is in service.

The acid container is bottle shaped, having a convex annular shoulder 15. The parts are so proportioned that when assembled, as shown in Figure 1, the lower rim of the cylinder will engage shoulder 15 of the acid container and loosely hold the container seated upon the cross bars 6, but will also hold the upper end of the container 90 against excessive lateral movement. The upper end of the ring will be held down in place by the cap 2. A stopper 16 is provided for the container, said stopper having a long stem 17 of a diameter considerably 100 smaller than the internal diameter of the neck of the container. When the apparatus as a whole is inverted the ring acts as a spacer to hold the acid container far enough away from the cap so that the acid can escape from the container. At this time the stopper will fall onto the cap but the movement will not be sufficient to permit the stem 17 to entirely leave the neck of the bottle.

The diameter of the cylindrical ring 12 is 110

somewhat smaller than the internal diameter of the ring 4, as a result of which the ring 12 may be tilted in the cage as well as moved vertically prior to the final assemblage of the 5 parts and the screwing down of the cap onto the tank.

Operation: Let it be assumed that the tank has received the proper amount of alkaline solution and that the acid container has received the proper amount of acid. The operator, under ordinary circumstances, will grasp the cage in one hand and the acid container in the other and will then proceed to introduce the container by slipping the neck 10 of the bottle up into the bottom of the ring 12, the container being tilted for the purpose and causing the ring to tilt as illustrated in Figure 2. When the container has been lifted high enough to permit the bottom 15 to clear the top of the lug 8, it is swung over and lowered onto the cross-bars 6. The lug 8, being placed equi-distantly from the two nearest bars 5, will of course retain the bottom of the acid container so long as the latter 20 remains seated. By the term "seated" is not meant necessarily a state of actual contact between the bottom of the container and the cross-bars of the cage, as the container may for practical purposes be regarded as seated 25 so long as it remains near enough to the cross-bars to prevent it from escaping laterally past the lug 8. When the container has become seated the ring 12 will stand vertically and its own weight and the fact that 30 it is surrounded by ring 4 and held on three sides by the bars 5 enable it to prevent the upper end of the container from swinging out through the open side of the cage. Hence 35 as long as the container remains seated it will be secure in the cage and consequently the cage and container may be handled 40 without much care and yet incur no risk of the container escaping from the cage. In fact, the cylindrical ring 12 may itself be 45 regarded as an auxiliary cage for the upper end of the container. When the container and cage have thus been assembled they are lowered into the tank 1 until the horizontal flange of the ring 4 rests upon the lugs 1^a 50 at the mouth of the tank. The cap 2 is then screwed down to close the tank and at the same time holds the ring 4 down close enough to the lugs to enable the cage to maintain its position. When the cap has 55 thus been screwed down it also holds the cylindrical ring 12 down so that it will engage the shoulders 15 of the acid container and prevent the container from escaping through the open side of the cage. When 60 the extinguisher is required for active service and is turned upside down the ring 12 supports the acid container and holds its mouth far enough away from the cap 2 to permit the contents to be discharged into 65 the solution surrounding it. At this time

the stopper 16 drops into contact with cap 2 but the stem 17 is long enough to remain within the mouth of the bottle so that the stopper will drop back into position to close the container at any time the extinguisher 70 is returned to normal upright non-acting position. As a result of this construction the insertion and removal of the acid container into and from the cage becomes a most simple matter. The ring 12 tilts readily and easily accommodates itself to the various positions of the container during the action of insertion or withdrawal. When the container is once in place it is automatically locked there and no ordinary shaking 80 or tilting will cause it to come out. No latches or locking devices of any kind need be manipulated by hand and no set screws or springs employed. One of the notable characteristics of the device is that the locking or retaining mechanism is manipulated not directly by the hand of the operator, but through the medium of the acid container. In this sense the operation is automatic for the ring 12 not only accommodates itself to the various positions of the acid container but automatically moves to acting position as soon as the container is seated. 85

While the lug 8, shown in Figures 1, 2 and 3 is adequate for all ordinary purposes and has the advantage of being readily fabricated, it may be of any desired width even to a complete ring 8^a as shown in Figure 5. In the latter case the ring completely surrounds the bottom of the acid container but may nevertheless be regarded as coming 90 within the same category. 100

Having thus described the invention what we claim as new and desire to secure by Letters Patent, is:— 105

1. In a fire extinguisher, a tank having a cap, an acid container, a cage for the container having an opening in the side large enough to admit it and having a lug at 110 the bottom for retaining the bottom of the acid container when the latter is in place in the cage, and a retainer for laterally confining the top of the acid container, said retainer being loosely connected to the cage 115 whereby it may yield upward and also tilt sideways to permit the container to pass over the lug while the container is being inserted, the retainer being approximately of sufficient length to simultaneously engage 120 the container and the cap when the parts are assembled. 125

2. A fire extinguisher having a tank provided with a cap, an acid container, a cage for the container having an opening in the side large enough to admit it, and having a lug at the bottom for retaining the bottom of the acid retainer when the latter is in place in the cage, and a retainer loosely connected to the cage whereby the acid con- 130

tainer may yield upward and also tilt sideways to permit the container to pass up over the lug while being inserted, the acid container having a rounded shoulder and the 5 retainer having a circular lower rim adapted to engage the rounded shoulder of the acid container, the retainer being substantially of such length as to simultaneously engage both the shoulder of the acid container and 10 the cap of the tank.

3. A fire extinguisher adapted to be inverted when in active service having a tank, a cap therefor, a bottle-shaped acid container, a cage for said acid container adapted to be suspended in the mouth of the tank, 15 said cage being open at one side for admitting the acid container, means for laterally confining the bottom of the acid container when the latter is seated in the cage, a 20 hollow cylinder adapted to engage the shoulder of the acid container for both con-

fining it laterally and supporting it when the device is inverted, said cylinder being adapted to be supported by the cap when the device is inverted, and a slot and pin connection between the cylinder and the cage for loosely confining the cylinder within the cage and permitting it to accommodate itself to various positions of the acid container when the latter is being introduced 30 into the cage.

4. A structure as specified in claim 3 in which the cylinder is located entirely within the cage and is vertically slotted and the cage has pins projecting radially inward 35 through said slots to loosely confine the cylinder and permit it to tilt as well as to move lengthwise of the cage.

In witness whereof, we have hereunto subscribed our names.

EARL J. SMITH.
HAROLD V. GLOS.
